VOLTAGE INDICATING CIRCUIT

John E. Maynard, Schenectady, N. Y., assignor to
General Electric Company, a corporation of
New York

Application February 8, 1943, Serial No. 475,221

7 Claims. (Cl. 250—40)

My invention relates to visual voltage indicating circuits and in particular to visual voltage indicating circuits for use in the tuning of radio receivers.

It is an object of my invention to provide an improved visual voltage indicating circuit for use as a tuning meter for radio receivers.

In receivers for frequency modulated radio waves, it is customary to employ a balanced frequency discriminator circuit as a means to demodulate the modulated radio frequency waves and to reproduce therefrom the modulating signals. Since the modulating signals appear as frequency deviations above and below the average carrier frequency, in the tuning of the receiver it is desirable, in order to obtain optimum reproduction of the signals by the receiver, to adjust the mid point of the discriminator's range of frequencies to match the average carrier frequency. Accordingly, it is an object of my invention to provide an improved tuning circuit by which the center frequency of a discriminator circuit may be adjusted to the proper value with ease and accuracy.

Another object of my invention is to provide an improved tuning indicator for frequency modulation receivers which is rugged and relatively inexpensive and which is particularly adapted for use on portable receivers.

One of the features of my invention is the use of an electron-ray tube having a fluorescent screen and a pair of electrodes. The potential of one of the electrodes varies in accordance with a potential being calibrated, while the potential of the other electrode is maintained at a value corresponding to the predetermined voltage to be indicated.

Another object of my invention is to provide an improved voltage indicating circuit employing an indicator of the cathode-ray type in which a first shadow width is maintained at a value corresponding to a predetermined voltage and a second shadow width varies in accordance with a voltage being adjusted.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 represents a portion of the frequency modulation receiver circuit embodying my invention

and Figs. 2—4 illustrate certain operating characteristics of my indicator circuit.

Referring to the drawing, I have shown an antenna 1 for receiving radio signals and supplying them to the radio frequency circuits 2 of a receiver. These circuits, which may be of any desired type, are indicated merely by the rectangle labeled 2 and include means for tuning the receiver to desired frequencies within a range of frequencies in response to rotation of a tuning control knob 3. The radio frequency voltages, after amplification in the circuits 2, and conversion to a constant intermediate frequency, if the receiver be of the superheterodyne type, are supplied to the tuned primary winding of the transformer of a frequency discriminator 11, the function of the discriminator circuit being to demodulate the modulated radio frequency input waves and to reproduce therefrom the modulating signals, which may be voice or music, and to supply them by means of conductor 12 to subsequent stages of the receiver. The indicating circuit 13 is provided to indicate the desired tuning condition of the receiver circuits.

The frequency discriminator circuit 11 is arranged to supply to the conductor 12 a potential which varies from a predetermined value, as for example ground potential, either positively or negatively depending upon the variations of the intermediate frequency from a desired fixed value. From the output of the discriminator, the signals are supplied by the lead 12 to further stages of amplification or to a sound reproducer.

The discriminator circuit 11 is of well-known form and comprises a transformer having a primary winding 14 and a secondary winding 15, both of these windings being tunable to the desired fixed intermediate frequency by means of capacitors 16 and 17. Operating potential for the preceding stages may be supplied from a suitable source, such as the battery 18 through primary winding 14, which is connected to ground for alternating currents by means of by-pass capacitor 19 and to the midpoint of secondary winding 15 through a condenser 20. The opposite terminals of the secondary winding 15 are connected to the respective anodes of diodes 21 and 22, the cathodes of these diodes being connected together for alternating currents through condenser 23 and for direct currents through resistances 24 and 25. The cathode of diode 22 is grounded and the midpoint between resistances 24 and 25 is connected to the midpoint of secondary winding 15 through a choke coil 26. In order to minimize the effect of resistor 25 on the quality value Q of

the primary winding 14, condenser 27 is connected in shunt with resistor 25 and in series with choke coil 26 connected between ground and the upper terminal of primary winding 14 through condenser 20. In addition, capacitor 27 functions also to by-pass resistor 25, thereby preventing radio frequency losses in resistance 25 from the passing of primary and secondary currents therethrough, and to filter radio frequency currents from lead 12 connected to audio output circuits.

In the desired operation of the discriminator circuit, when the tuning control of the radio receiver is adjusted for accurate resonance with the received carrier wave and the intermediate frequency has the value to which the primary and the secondary windings 14 and 15 are each tuned, the voltage across the secondary winding of the transformer, in accordance with well-known theory, is displaced in phase from the voltage across the primary by 90°. With the connection shown, the voltage of the primary is connected in series with one-half of the secondary across discharge device 21 and condenser 23, and the primary is connected in series with the other half of the secondary across discharge device 22. Because of the quadrature relation between the primary and secondary voltages, the voltage on one-half of the secondary leads the voltage on the primary by 90°, whereas that on the other half of the secondary lags behind the voltage on the primary by 90°. Thus, the voltages applied to the two diodes 21 and 22, when the intermediate frequency is at its desired value, are equal and accordingly equal values of unidirectional current flow through each of the diodes and hence through resistances 24 and 25. It will be observed that the diodes are so poled that the voltages across the two resistances 24 and 25 are opposite in polarity in the circuit between conductor 12 and ground with the result that conductor 12 is at ground potential when the intermediate frequency is at the desired value.

The quadrature relation between the primary and secondary voltages of the discriminator transformer exists, however, only when the oscillations supplied thereto have the desired intermediate frequency. If this frequency changes in either direction, the phase of the secondary voltage varies from its 90° relation with the primary voltage in one direction or the other, dependent upon whether the frequency increases or decreases. If the frequency increases, the phase shift may be in such a direction that the voltage on the upper half of the secondary winding approaches the aiding relation with the primary voltage, whereas that on the lower half of the secondary winding approaches the opposing relation with the primary voltage. Thus, the voltage applied to diode 21 increases and that applied to diode 22 decreases with the result that the unidirectional potential on resistance 24 increases, whereas that on resistance 25 decreases and the conductor 12 thus becomes positive with respect to ground. On the other hand, if the intermediate frequency decreases, an opposite shift in phase of the secondary voltage occurs with the result that the larger alternating current voltage is supplied to diode 22 and the potential on resistance 25 increases and that on resistance 24 decreases and the conductor 12 is driven negative with respect to ground.

In order to determine that the receiver circuits are tuned effectively to the same frequency to which the windings of the discriminator circuit

are tuned so that, in the presence of an unmodulated carrier wave, the conductor 12 is at ground potential, the indicating circuit 13 is provided and comprises the amplifier 30 and the electron-ray tube 31. Amplifier 30 is shown as a pentode having its screen electrode 32 connected directly to the anode 33 and its suppressor grid 34 connected directly to the cathode 35, the control electrode 36 being connected to the conductor 12 through resistor 37. With this circuit, the pentode operates as a triode amplifier and provides the advantages of a high transconductance offered by a pentode type of electron discharge device. Of course, any triode may be used and the sensitivity of the circuit depends upon the transconductance of the particular triode used. The resistor 37 is of a high value, for example, of the order of 1 megohm, in order to avoid loading the input circuit of the amplifier by grid current in the device 30, as well as to prevent any loading of the output circuits of the discriminator.

The electron-ray tube 31 is a well-known twin type electric eye tube. It contains two control electrodes 38 and 39 for producing two independent angles on the fluorescent screen or anode 40 and a cap 40', located in the tube approximately as shown in Fig. 1, and which causes the anode to appear as a luminous ring to a person viewing the indicating end of the tube. In this type of tuning indicator, electrons travel radially outwardly from the cathode 41 to the fluorescent screen or anode 40 in a wide beam and the extent of the surface of the anode reached by the electron beam is determined by the voltage on the electrodes 38 and 39. The more positive these electrodes are with respect to cathode 41, the greater is the area of the anode covered by the beam and the smaller the shadow angles cast by these electrodes. Operating potential for the anode 40 is provided from any suitable source, such as the battery 42, through a voltage dropping resistor 43 and the anode 40 of the electron-ray tube is connected to anode 33 of the amplifier 30 through a resistor 44 which functions as a load resistor for the amplifier. Resistor 44 is of large value, for example, 0.5 megohm, in order to provide a wide range of control voltage for the control electrode 38 of the electron-ray tube 31.

A voltage divider, comprising resistors 45, 46, and 47, is connected in series with voltage dropping resistor 43 across the battery 42 in order to provide suitable bias voltages for the tubes 30 and 31. Cathode 35 of the amplifier 30 is connected to an adjustable point on resistor 47 of this voltage divider and both control electrode 39 and cathode 41 of the electron-ray tube are connected to the common point of resistors 45 and 46. In some applications it may be desirable to connect electrode 39 to an intermediate point on either resistor 45 or resistor 46 in order to maintain electrode 39 at a fixed positive or negative potential with respect to cathode 41 and provide a desired calibration pattern.

In the adjustment and operation of the indicator circuit 13, the voltage difference between cathode 41 and anode 40 of the electron-ray tube, that is, the unidirectional potential across resistor 45, determines the brightness of the indicator pattern and also affects the opening angle of the indicator patterns determined by electrodes 38 and 39. The indicator pattern determined by electrode 39 functions as and is hereinafter referred to as the calibrated or reference pattern. The shadow angle determined by electrode 38,

which is hereinafter called the indicator pattern, is adjusted to show the same angle of opening as that shown on the calibrated or reference pattern for a predetermined voltage to be indicated. In a frequency modulation receiver, when the indicator 13 is used in conjunction with the discriminator 11, the voltage to be indicated, that is, the potential of conductor 12 in the absence of a modulating signal in the receiver circuit, is ground potential or zero voltage. In adjusting the indicator 13 so that the indicator angle or pattern produced by control electrode 38 matches that of the calibrated pattern when there is zero voltage on conductor 12, control electrode 36 is connected directly to ground and the potential between control electrode 36 and cathode 35 is adjusted by means of the contact arm 48 on resistor 47 so that the same angle of opening is shown on both the indicator and calibrator patterns.

When the above adjustment has been made, the indicator circuit is ready for operation. Input voltages more positive than zero cause more current to flow in resistor 44 and make the control voltage of electrode 38 less positive, opening the shadow angle of the indicator pattern. Condenser 49 is provided to remove audio frequency voltages from control electrode 36 and give an increased clearness of the indicator pattern. Input voltages on conductor 12 of negative polarity cause less current to flow in resistor 44 and make the control voltage of electrode 38 more positive than the calibrated electrode 39 and are effective to decrease the angle of the indicator pattern. In this way, in the tuning of the receiver, the cross-over point of the discriminator output circuit, where the voltage on conductor 12 changes from positive to negative, and hence the position of the tuning control knob at which the receiver is tuned precisely to the received carrier wave, may be determined with ease and accuracy.

The operation of the indicator circuit may be illustrated by Figs. 2-4. In Fig. 2, the desired condition of precise tuning, where the output voltage of the discriminator circuit is zero, is shown. The reference pattern 50 is held constant at an angle determined by the potential of electrode 39 with respect to cathode 41. The opening angle of the indicator pattern 51, determined by the potential of electrode 38 with respect to cathode 41, under the desired condition of tuning is equal to the angle of the reference pattern. Fig. 3 illustrates the condition when the frequency of the voltage applied to the discriminator circuits is higher than that to which these circuits are tuned. The output voltages of the discriminator is then positive and the shadow angle 52 of the indicator pattern is larger than that of the reference pattern 50. Fig. 4 illustrates the condition when the output voltage of the discriminator is negative and the shadow angle 53 of the indicator pattern is smaller than that of the reference pattern 50.

The indicator thus disclosed provides a circuit and apparatus, particularly adapted for tuning frequency modulation receivers, which is more rugged and less expensive than instrument types of indicators, such as microammeters. It is especially adapted for use in portable receivers where instruments are affected by vibration and similar shocks. Since a reference pattern is provided which indicates a desired tuning condition, the receiver may easily be adjusted so that the indicator pattern matches this reference pattern. While such accuracy of tuning is desirable in any type of radio receiver, whether being used for

the reception of broadcast signals or other types of signals, it is particularly desirable for tuning accurately to the center frequency of a wide band in a frequency modulation system or in any type of receiver using a discriminator transformer.

Since the electron-ray tube 31 is operated with its cathode considerably above ground potential, a wide range of potentials for electrode 38 is permitted so that wide angles of indication for the indicator pattern from zero to substantially 180° may be used and hence the maximum visual sensitivity of the indicator utilized. It is apparent, of course, that the cathode of the device 31 may be operated at ground potential, such operation limiting the opening angles of the indicator pattern to approximately 90°. Since the entire bias system for the tubes 30 and 31 is contained in the same network, voltage variations in this network affect all unidirectional tube potentials in the same manner and in the same per cent so that calibration accuracy is maintained despite such variations.

In this respect, it is noted that sensitivity of the circuit to variation of the input voltage is a function of the amplification of amplifier 30, the control sensitivity of the electron-ray tube 31, and the visual judgment of the observer but has no relation to the total amount of voltage variation in the voltage to be indicated. By this is meant that an adjustment of the discriminator output voltage can be made to an accuracy of a definite amount of voltage variation from zero potential regardless of the input potential of the discriminator.

By way of illustration only and not in any sense by way of limitation, the following values are given for a particular frequency modulating receiver embodying my invention. In this receiver a type 6SH7 tube was employed as the amplifier 30 and a type 6AD6-G tube as the electron-ray tube 31. When the value of resistor 44 was 0.5 megohm and of resistor 37, 1 megohm, the bias potential between contact 48 and ground was adjusted to 3 volts and the voltage of anode 49 was approximately 200 volts and of cathode 41, approximately 100 volts. It was found in a particular test that, for an opening angle of 100° used for the calibration pattern angle, tuning casually, the incoming signal frequency could be set within .2 volt of the zero voltage cross-over point of the discriminator, while tuning with a reasonable amount of care, a signal frequency could be set within .1 volt or less of the discriminator cross-over voltage.

While I have shown my indicator circuit as used in conjunction with a discriminator of a frequency modulation receiver, it may be used for other purposes such as, for example, to obtain zero voltage indications in a bridge circuit. It is apparent, therefore, that it may be used wherever it is desired to compare a voltage being measured with a standard voltage and it will be understood that while I have shown a particular embodiment of my invention, I do not wish to be limited thereto since various modifications may be made, and I contemplate by the appended claims to cover any such modifications as fall within the true spirit and scope of my invention.

What I claim as new and desire to secure by Letters Patent of the United States, is:

1. A voltage indicator comprising a resistor having a pair of terminals and an intermediate contact, a source of unidirectional potential connected across said terminals, cathode-ray indi-

cator means capable of producing a pair of independent electrical shadows and comprising an anode, a cathode, and a pair of control electrodes, said anode being connected to one of said terminals and said cathode and one of said electrodes being connected to said intermediate contact, thereby to provide a first shadow angle of substantially constant value in said cathode ray means, and means supplying between said other electrode and said anode a potential varying in accordance with a voltage to be calibrated, thereby to provide a second shadow angle in said cathode ray means for comparison with said first shadow angle.

2. A voltage indicator comprising a resistor having a pair of terminals and a pair of intermediate contacts, a source of unidirectional potential connected across said terminals, cathode ray indicator means capable of producing a pair of independent electrical shadows and comprising an anode, a cathode, and a pair of control electrodes, said anode being connected to one of said terminals and said cathode and one of said electrodes being connected to one of said intermediate contacts, thereby to provide a first shadow angle of substantially constant value in said cathode ray means, and means supplying between said other electrode and said anode a potential varying in accordance with a voltage to be calibrated, thereby to provide a second shadow angle in said cathode ray means for comparison with said first shadow angle, and means including the other of said intermediate contacts for adjusting said variable potential to calibrate said cathode ray indicator means.

3. In a receiver for frequency modulated radio waves, the combination of a balanced frequency discriminator, said discriminator having an output circuit, and means for indicating the tuning of said receiver, said means comprising cathode ray indicator means capable of producing a pair of independent shadows and comprising an anode, a cathode and a pair of control electrodes, means connected to said output circuit to supply between said anode and one of said electrodes a unidirectional potential varying in accordance with the voltage of said output circuit, thereby to produce in said cathode ray means a variable shadow angle indicating the tuning condition of said receiver, and means to supply between said anode and the other of said electrodes a unidirectional potential of substantially constant value thereby to produce in said cathode ray means a second shadow angle of substantially constant width, the value of said substantially constant unidirectional potential and the width of said constant shadow angle being substantially the same as the value of said variable potential and the width of said variable shadow angle, respectively, at a desired tuning condition of said receiver.

4. A tuning indicator for a frequency modulation receiving apparatus comprising a balanced discriminator having an output circuit, a cathode ray indicating device capable of producing a pair of independent shadows and comprising a cathode, an anode and a pair of control electrodes, means for supplying between said anode and said cathode a substantially constant unidirectional potential, means for fixing the potential of one of said control electrodes with respect to said cathode thereby to provide in said cathode ray device a first shadow angle of substantially constant width, a resistor connected between said anode and the other of said control electrodes,

and means connected to said output circuit for supplying to said resistor a current varying in accordance with the voltage of said output circuit thereby to control the potential of said second control electrode with respect to said cathode and to produce in said cathode ray device a second shadow angle of variable width indicating the tuning condition of said receiving apparatus.

5. A tuning indicator for a frequency modulation receiving apparatus comprising a balanced discriminator having an output circuit, a cathode ray indicating device capable of producing a pair of independent shadows and comprising a cathode, an anode and a pair of control electrodes, means for supplying between said anode and said cathode a substantially constant unidirectional potential, means for fixing the potential of one of said control electrodes with respect to said cathode thereby to provide in said cathode ray device a first shadow angle of substantially constant width, a resistor connected between said anode and the other of said control electrodes, means connected to said output circuit for supplying to said resistor a current varying in accordance with the voltage of said output circuit thereby to control the potential of said second control electrode with respect to said cathode and to produce in said cathode ray device a second shadow angle of variable width indicating the tuning condition of said receiving apparatus, and means for adjusting said current to render said shadow angles substantially equal at a desired tuning condition of said receiving apparatus.

6. A tuning indicator for a frequency modulation receiving apparatus comprising a balanced discriminator having an output circuit, a cathode ray indicating device capable of producing a pair of independent shadows and comprising a cathode, an anode and a pair of control electrodes, a source of electric current supply connected to maintain between said anode and said cathode a substantially constant potential and to fix the potential of one of said control electrodes with respect to said cathode thereby to produce in said cathode ray device a first shadow angle of substantially constant width, a resistor connected between said anode and the other of said control electrodes, an electric discharge device connected to conduct current from said source through said resistor, and means connected to said output circuit for controlling the intensity of said current in accordance with the voltage of said output circuit thereby to control the potential of said other control electrode with respect to said cathode and to produce in said cathode ray device a second shadow angle of variable width indicating the tuning condition of said receiving apparatus.

7. A tuning indicator for a frequency modulation receiving apparatus comprising a balanced discriminator having an output circuit, a cathode ray indicating device capable of producing a pair of independent shadows and comprising a cathode, an anode and a pair of control electrodes, a source of electric current supply connected to maintain between said anode and said cathode a substantially constant potential and to fix the potential of one of said control electrodes with respect to said cathode thereby to produce in said cathode ray device a first shadow angle of substantially constant width, a resistor connected between said anode and the other of said control electrodes, an electric discharge device connected to conduct current from said source through said resistor, means connected to said output circuit

for controlling the intensity of said current in accordance with the voltage of said output circuit thereby to control the potential of the other of said control electrodes with respect to said cathode and to produce in said cathode ray device a second shadow angle of variable width indicating the tuning condition of said receiving

apparatus, and means for adjusting the potential of said other control electrode to render said shadow angles of substantially equal width when the voltage of said output circuit is substantially zero.

JOHN E. MAYNARD.
